UNITED STATES PATENT OFFICE.

LEONARD JOHNSON, OF NORTHAMPTON, MASSACHUSETTS, ASSIGNOR TO OTTO A. BELGER, OF NEWTONVILLE, MASSACHUSETTS.

WASTE-COLLECTOR FOR COMBING-MACHINES.

1,369,176.

Specification of Letters Patent. Patented Feb. 22, 1921.

Application filed July 22, 1920. Serial No. 398,047.

To all whom it may concern:

Be it known that I, LEONARD JOHNSON, a citizen of the United States, residing at Northampton, county of Hampshire, State 5 of Massachusetts, have invented an Improvement in Waste-Collectors for Combing-Machines, of which the following description, in connection with the accompanying drawing, is a specification, like characters on the drawing representing like parts.

This invention relates to combing machines and particularly to combing machines which are provided with a waste collector of the general type shown in United States patent to Roth, No. 905,233, dated December 1, 1908, or United States patent to Belger, No. 1,106,073, dated August 4, 1914. The waste collectors shown 15 in these patents comprise a casing which incloses the combing member and the stripping member, an air-exhausting mechanism for creating an air current through the casing which takes the waste off from the stripping member, a rotary perforated screen situated within the casing adjacent the exit end thereof and arranged so that the air current passes through the screen whereby the waste is drawn onto the screen; 20 and a stationary shield within the screen which protects a portion of the periphery thereof from the action of the air-exhausting device with the result that the waste which is drawn onto that portion of the 25 perforated screen through which the air current is passing will be carried by the rotation of the screen around to that portion thereof which is protected from the air current from which it is removed and drops 30 into a can or other similar receptacle suitably placed for this purpose.

In the operation of waste collectors of this type the waste usually is removed from the screen in the form of a fleece or sliver 45 and being of a fluffy nature it will pile up more or less rapidly in the can or receptacle. As a result, it is necessary for the attendant to pack this waste down in to the can by hand in order to prevent it from 50 running over the top of the can. This operation of manually packing the waste into the can as it accumulates is not always attended to faithfully by the attendant with the result that frequently the can becomes

filled and then the waste will drop over the 55 top of the can onto the floor.

The object of my present invention is to provide a novel device for automatically packing the waste into the can as it is delivered from the screen, which device not 60 only prevents the possibility of the loose fluffy waste overflowing the can, but also packs the waste more firmly than would ordinarily be done by hand, thus requiring less frequent attention so far as emptying 65 the can is concerned.

In order to give an understanding of my invention, I have illustrated in the drawings a selected embodiment thereof which will now be described, after which the novel 70 features will be pointed out in the appended claims.

The figure illustrates a portion of a combing machine having my improvement applied thereto.

Since my present invention relates simply to the waste collector and the means for packing the waste into the can or receptacle, I have not deemed it necessary to illustrate a complete combing machine, but 80 have contented myself with showing only a sufficient portion of a combing machine and its waste collector to enable my invention to be understood.

1 indicates a portion of the frame of a 85 combing machine, 2 indicates the combing member and 3 the stripper brush by which the waste is stripped from the combing member during the operation of the machine. These parts are or may be all as 90 usual in combing machines and form no part of my present invention.

Associated with the comber and the stripper is a waste collector having a construction somewhat similar to that illustrated in Patent No. 905,233, dated December 1, 1908, in that it comprises a casing 4 which incloses the combing member and the stripper brush, an air-exhaust apparatus or fan 5 which is connected to the casing by 100 a pipe or conduit 6, and a perforated rotary screen 7 situated adjacent the exit end of the casing and arranged so that the air current which is drawn through the casing by the fan will pass through the rotary screen. Situated within this rotary screen 105 is a shield 8 which covers or protects all of the screen except the side toward the strip-

per. The current of air thus established through the casing 4 will draw the waste from the stripper, as indicated at 9, and this waste will be deposited on the portion 5 of the screen which is exposed by the shield and through which the air current passes. As the screen rotates the waste which is accumulated thereon is carried under a compressing roll 10 and over the portion of the 10 screen which is protected by the shield and which is not subjected to the action of the air-forcing device. This waste which is on the protected portion of the screen is thus free to be removed therefrom, and as 15 the screen rotates, it will separate from the screen and drop by gravity into a can or receptacle 11 which is situated beneath the screen for this purpose.

The parts thus far described are or may 20 be all as shown in the above-mentioned patent to Roth, No. 905,233, December 1, 1908, and as the operation of said parts is fully described in said patent, it will not be necessary to enter into a more detailed description 25 herein.

The waste which is taken off from the screen 7 is in a more or less light and fluffy condition and it will, therefore, build up rather rapidly in the can 11. As stated 30 above, it has heretofore been the common practice for the attendant to periodically pack the waste into the can by hand in order to prevent the waste from running over the top of the can. In accordance with my invention, I propose to employ a waste-packing roll which is yieldingly held in contact with the rotating screen at about the point where 35 the waste is removed from the screen and which will be rotated with the screen. This 40 waste-packing roll serves to automatically pack the waste into the can when the can becomes filled and it will operate to apply sufficient pressure to the waste so that the latter will be packed into the can more firmly 45 than is usually done by hand, thus prolonging the time which may elapse before it is necessary to empty the can. This waste-packing roll is indicated at 12 and is in the form of a cylinder which is shown as suitably supported in brackets 13 carried by the 50 frame of the machine. Suitable means are provided for yieldingly holding the packing roll 12 against the rotary screen 7. This can conveniently be done by making the 55 brackets 13 with the inclined slots 14 in which are slidably mounted the bearings 15 for the shaft 16 of the roll 12 and providing 60 suitable springs 17 which tend to force the bearings downwardly in the slots thereby holding the packing roll 12 yieldingly 65 against the screen. Any other suitable means for thus holding the roll yieldingly against the rotary screen may be provided without departing from the invention.

65 The packing roll 12 may be rotated either

by frictional contact with the screen 7 or may be positively driven as desired. If it is to be positively driven, any suitable means for this purpose may be employed, such, for instance, as gears which connect it to the 70 rotary screen.

With this arrangement the waste collector will operate all as shown in said patent until the light fluffy waste mass in the can 11 is built up to the top of the can. At this 75 time the combined action of the packing roll 12 and rotary screen 7 will operate to force the waste into the can as it is delivered from the screen, thus preventing the waste from spilling over the top of the can. This positive feeding of the waste into the can by the packing roll 12 will compress the waste in the can 11. I find from demonstration that with the packing roll 12 it is possible to pack 80 forty or fifty per cent. more waste into the can than is usually done by the hand method. The use of this packing roll has the advantage that it requires no attention on the part of the attendant. Consequently, since 85 the attendant is relieved from the necessity of frequently packing the waste into the can by hand to prevent its running over, he can devote his entire time to the supervision of the machine and is thus able to look after more machines than is possible where a part 90 of his time is necessary in packing the waste into the can by hand.

All danger of the waste spilling over onto the floor is thus avoided and this is an advantage because the waste which does thus 100 spill onto the floor has to be sold as sweepings and at a considerable loss.

The roll 12 is shown as supported in two brackets 13, the one nearest the observer being broken out in the drawings. These 105 brackets 13 are secured to arms 18 forming part of the frame 1 by means of bolts 19, said arms 18 constituting the means for supporting the rotary screen 7.

The manner of supporting the roll 12 110 will, however, be varied more or less depending on the construction of the combing machine with which the invention is used.

I claim:

1. In a combing machine, the combination 115 with a combing member and a brush, of a perforated rotary screen, an air-exhausting means connected to said screen and operating to generate an air current therethrough whereby the waste from the brush is collected on the screen, means for removing the waste from the screen, a can or receptacle to receive said waste, and means co-operating with the screen for packing the waste into the can. 120

2. In a combing machine, the combination 125 with a combing member and a brush, of a perforated rotary screen, an air-exhausting means connected to said screen and operating to generate an air current therethrough 130

whereby the waste from the brush is collected on the screen, means for removing the waste from the screen, a can or receptacle to receive said waste, and a packing 5 roll coöperating with the screen to pack the waste in the can.

3. In a combing machine, the combination with a combing member, and a brush, of a perforated rotary screen, an air-exhausting 10 means connected to said screen and operating to generate an air current therethrough

whereby the waste from the brush is collected on the screen, means for removing the waste from the screen, a can or receptacle to receive said waste, and a packing 15 roll yieldingly held against the screen at a point where the waste is removed therefrom and coöperating therewith to pack the waste in the can.

In testimony whereof I have signed my 20 name to this specification.

LEONARD JOHNSON.
